UNITED STATES PATENT OFFICE.

SYLVANUS A. REED, OF NEW YORK, N. Y., ASSIGNOR TO THE REED PROPELLER CO. INC., OF NEW YORK, N. Y., A CORPORATION OF NEW YORK.

AERONAUTICAL PROPELLER.

Application filed May 12, 1924. Serial No. 712,645.

This invention relates generally to propellers for aeronautical purposes and it is well adapted for use in connection with metal propellers.

5 In my U. S. Patent No. 1, 463,556, dated July 31, 1923, and also in my Patent No. 1,518,410, dated Dec. 9, 1924, I disclose certain types of metal aeronautical propellers, and my present improvements are also applicable to said general type, but, of course, 10 are not in any way limited thereto.

In metal aeronautical propellers, and especially those of the solid type with thin sections and also those with separate blades attached to a metal hub and of the general types shown in some of my other applications for patents, one of the principal problems is to reduce the aggregate weight, and my present invention pertains to improvements 20 in central construction of blades and attaching hub, which result in a considerable reduction in weight over previous constructions. The centrifugal force exerted in the operation of aeronautical propellers is very 25 high being seldom less than eight or ten tons on each blade, and the types of blade attachment familiar in fans and blowers of low centrifugal force, are not practical for aeronautical propellers, especially under the 30 stress of long continued-service. One part of my improvements includes means for attaching the separate blades directly to the hub by a peculiar interhooking of the parts, so that as regards centrifugal force, the connections 35 are independent of bolts, rivets, sockets, screw-threads, welds, clamps or other secondary means. Another feature of my novel attaching means is that it is limited solely by the bending moment, and shearing stress of a 40 wide and evenly distributed part of the blade at its strongest part, and more specifically stated the construction and arrangement is the inter-hooking of hooks bent up from the blade material, with suitably engaging 45 members or lugs on the driving member or hub.

With these and other objects in view, my invention will be more fully described, illustrated in the drawings and then particularly pointed out in the claims.

In the said drawings:

Fig. 1, is a perspective view of a three-bladed propeller with its hub and shows an embodiment of my invention.

55 Fig. 2, is a perspective view of the hub

shown as detached.

Fig. 3, is a perspective view of one of the blades shown as detached.

Fig. 4, is a perspective view of modified form of my invention.

Referring to the drawings, 1 is a hollow body preferably cylindrical in form and constitutes the attaching member or hub, and is provided with the usual key-way 2, for securing said member to the drive-shaft 65 which is not shown.

Upon the exterior of the member 1, and preferably integral therewith, are arranged a series of pairs of anchor parts or lugs 3, 4, and 5, 6, and 7, 8, the lugs 3, 4 and 5 of each 70 pair being disposed near one end of the hub, while the others are located near the other end. Each pair of lugs is designed to engage with a pair of hooks on the inner ends of the respective propeller blades 75 9, 10 and 11. The lugs or fins are shown as angular and somewhat wedge-shaped, but the blade-hooks may be formed or have a twist so that said fins may be rectangular or other shape, and the free or un-engaged face 80 of each fin may blend gradually into the wall of the member 1, to give added strength thereto, as indicated by the gradually curved surface at 12.

The separate blades 9, 10 and 11, are preferably of solid metal and are suitably shaped and provided with the desired pitch-angles. The inner or root end of each blade, which is the thickest part, is made relatively wide and has the center of its inner edge notched 85 at 13, to provide the prongs or tongues 14 and 15, which are bent at 16, and 17, respectively, in opposite directions as shown in Fig. 3. The base 16 and 17 of each hooked prong thus formed is comparatively long 90 and the strength thereof is dependent upon the bending moment and the shearing stress of the strongest part of the blade, the metal for which is especially adapted to this structure, because of its tensile strength, elastic 100 limit and other physical properties, aluminum alloys, and particularly duralumin being well adapted for this use.

The inner end of each blade bears against the exterior of the hub 1, on a diagonal or 105 helical line and the engaging lugs are accordingly in staggered positions, as shown in Fig. 2. Considering now that the hooks or prongs 14 and 15, of blade 9, are in engagement with lugs 3 and 4, it will be noted 110

that hook 14 engages the right side of lug 3, while the oppositely projecting hook 15 engages its lug 4, upon the left hand side thereof. The same arrangement is true of 5 the other two blades 10 and 11, and their inter-engaging lugs.

In order to position the blades on their respective lugs, I use bolts 18, which are, however, so disposed and located that the 10 centrifugal force exerted upon the blades in the operation of the propeller, does not have to be taken up by said bolts, as the integral lugs and integral hooks of the blades do this work.

15 The hooks 14 and 15, and also the positioning lugs on the hub 1, are either or both provided with slots for the passage of the bolts 18. In Fig. 2, the lugs are shown as provided with the bolt-slots 31, while in 20 Fig. 3, the hooks are shown as formed with slots 30. These slots permit of a shifting or alteration in the blade angles when desired, by merely loosening the bolts and turning the blades slightly on their longitudinal axes and then resetting the bolts to retain the adjustment, after resetting or changing the filler blocks to accommodate the new angle.

25 In Fig. 4, I show a modification of my invention by using two oppositely extending propeller blades 20 and 21. In this structure, the inner or root portion of each blade is notched at its edge at 22, so as to provide two substantial and strong prongs or 30 hooks 23 and 24, which are alike and which are first bent slightly at 25, to position the hook and then bent more sharply at 26, to provide the beak for engaging the respective lugs or fins 28 and 29, a pair of which is 35 located upon opposite sides of the hub.

40 In each case the inner end of each blade between the hooks or prongs abuts on and crosses the driving-axis at an angle substantially appropriate for the desired pitch of 45 the blade. The fitting of the abutting edges of the inner edge of each blade against the surface of the hub 1, may be so snug and intimate as to cause the same to participate in the transmission of thrust which is mainly 50 the duty of the hooks and lugs, for it will be noted that there is an extended contact between said abutting parts and that the line of the same is diagonal with respect to the exterior of said hub. Obviously this intimacy of these abutting parts may be increased by letting the end-edge of the blade sink slightly into the surface of the hub-member, and the latter may be grooved for that purpose.

55 The construction and formation of the propeller blades and their pitch angles may be in accordance with the descriptions given in my said patent and pending application for patent, though other forms may be used 60 with the particular improvements herein dis-

closed.

I wish to be understood as not limiting my invention to the particular forms herein set forth, as it is manifest that modifications may be made in the several parts thereof, 70 without, however, departing from the spirit of my invention.

Having thus described my invention, what I claim and desire to secure by Letters Patent is:

75 1. An aeronautical propeller including separate blades having hub-straddling inner ends, a hub in straddling engagement with said blades, and hook members mounted on said inner ends of the blades, and said hub 80 being provided with blade-attaching means spaced apart diagonally thereon and engaged by said hook-members for transmission of torque and thrust.

85 2. An aeronautical propeller including separate blades having hook-members formed on the blade root portions and a driving member having lug-members formed integrally thereon for anchoring engagement with said hook-members, the lug-members 90 engaged by the hook-members of any one blade being spaced apart longitudinally of and disposed on different longitudinal lines of said driving-member.

95 3. An aeronautical propeller including separable blades and a driving-member, the inner ends of said blades being forked and the fork-prongs being arranged to be placed in straddling relation to the driving-member, and hook means for securing the fork-prongs to said driving-member.

100 4. An aeronautical propeller including separable blades and a hub, the root portions of the blades being forked and the fork-prongs being arranged to be placed in diagonally straddling relation to the hub, and lugs integrally formed on said hub arranged to be placed in anchoring engagement with said fork-prongs.

105 5. An aeronautical propeller including separable blades and a hub, the root portions of the blades being forked and hooked and the fork-prongs being arranged to be placed in straddling relation to said hub, lugs integrally formed on said hub arranged to engage said hooked fork-prongs, and means 110 for securing said parts together.

115 6. An aeronautical propeller including separate blades and a driving-member therefor, both said blades and driving-member being provided with inter-hooking parts, and means for adjustably connecting them together to permit of angular displacement of the blades for varying the pitch thereof.

120 7. An aeronautical propeller including separable blades and a hub, the root portions of the blades being forked and the fork-prongs being hooked and arranged to be placed in diagonally straddling relation to the hub, and lugs inherently on said hub ar- 125

ranged to engage said fork prongs, and means for adjustably securing said fork prongs and said lugs together to permit of angular displacement of the blades for causing pitch change of said blades.

8. In aeronautical propeller construction, separate blades, a driving-member provided with blade-attaching means spaced apart peripherally and longitudinally of said driving-member for each blade, said blades each

having its root portion provided with attaching-projections spaced apart substantially in the direction of the width of the blade and constructed and arranged to be placed in engagement with said blade-attaching means on the driving-member. 15

In testimony whereof, I have hereunto set my hand.

SYLVANUS A. REED.
